UNITED STATES PATENT OFFICE.

CHARLES H. CROWELL, OF BROOKLYN, NEW YORK.

PROCESS OF MAKING CLOTH GUMMED TAPE.

1,276,730.

Specification of Letters Patent. Patented Aug. 27, 1918.

Application filed March 8, 1917. Serial No. 153,328.

To all whom it may concern:

Be it known that I, CHARLES H. CROWELL, a citizen of the United States, and resident of the borough of Brooklyn, county of Kings, city and State of New York, have made a certain new and useful Invention Relating to Processes of Making Cloth Gummed Tape, of which the following is a specification, taken in connection with the accompanying drawing, which forms part of the same.

This invention relates especially to gummed tape such as may be used for sealing cartons, packages, or for other purposes, in which the relatively narrow strips of tape are cut from the end of the sheet or web of gummed cloth in which the warp threads are for best results more numerous and preferably also stronger and firmer than the filling threads. By advancing a web of such gummed cloth intermittently a distance equal to the width of the gummed strips desired these strips may be successively severed transversely to the length of the web so that the stronger warp threads are arranged transversely to and preferably substantially perpendicularly to the length of the gummed strips so that they have a maximum of transverse strength, and if desired, the gummed strips may be fed or moved transversely across the end of the web from which they are cut and simultaneously moistened so that they are delivered in condition for use.

The accompanying diagrammatic drawing shows in Figure 1 a perspective view of an arrangement for severing gummed strips from one or more webs.

Fig. 2 is an enlarged plan view showing the relation of the severed strip to the web; and

Fig. 3 is an enlarged diagrammatic section taken longitudinally of the gummed tape strip.

For sealing and other finishing purposes cloth gummed tape does not in many cases need a very high degree of longitudinal strength while its transverse strength is considerably more important because the strip is usually employed to cover a seam extending longitudinally of the strip and adhesively hold the edges of this seam together. The number and character of the threads extending transversely of the strip therefore determine its efficiency and strength under

such conditions while the longitudinally extending threads are of relatively little importance so long as a fair degree of longitudinal strength is preserved and so long as the strip is not unduly stiffened in this way. For this reason it is desirable to form cloth gummed strips from specially woven cloth in which the warp threads are not only stronger and harder because of the different twist given them, but also preferably woven under much greater tension than the filling or woof threads.

In making cloth gummed tape suitable for ordinary package sealing, cloth having warp and filling threads of such size, weight and character as generally correspond with what are used in print cloths, may be employed and the count of the warp threads is preferably much greater than that of the filling threads and may advantageously be made about twice as great. For example, when No. 28 or 30 warp thread is used the warp count may be about 60 per inch, while the filling threads preferably of much softer, weaker material, may be only about 30 per inch which means a considerable saving in the weight and cost of the cloth. It is also desirable for some purposes to have the warp threads stretched considerably tighter than usual during the weaving process so that they are relatively straighter in the finished cloth, the softer filling threads having a more zigzag or irregular arrangement between them. Such specially woven cloth must, of course, be severed into transversely extending strips in order to utilize the strength of the warp threads to best advantage for gummed tape purposes. It is also of course apparent that the cloth preferably after having been filled and finished in any suitable way so as to secure the desired degree of imperviousness may be first severed and then rendered adhesive in some cases just before its utilization, or the cloth may be first gummed and then severed into the individual gummed strips preferably after having been slit into web rolls in which the web has a width corresponding to the length of the gummed strips desired. It is not of course necessary that the strips shall in all cases extend exactly perpendicularly to the warp threads so long as these stronger warp threads extend across the strip to such extent as to strengthen it materially against transverse strain as compared to the

strength of the weaker filling threads, although it is of course still more desirable to have the warp threads extend substantially perpendicular to the length of the 5 gummed strips. It is of course understood that for heavier service larger and stronger warp threads may be used and for some purposes warp threads such as used in some 10 grades of sheeting may be advantageously employed, the filling threads being preferably less numerous, although where the warp threads are relatively stronger and harder considerable increase in the transverse strength of the gummed tape is 15 cured by severing the strips transversely of the warp threads even where the filling count more nearly approaches that of the warp threads.

In Fig. 2 the web 1 of gummed cloth preferably woven with the warp threads, such as 20 24, arranged considerably closer together than the transversely extending filling threads which are not shown may be dyed, filled and finished in any suitable way, preferably so that it is substantially completely filled and practically impervious before the gum coating is applied to the cloth. It is also desirable to keep the cloth sufficiently under tension during these finishing operations 30 so that the warp threads are kept substantially extended and straight. This web of gummed cloth may by any suitable devices be severed into gummed tape strips such as 21 by cutting the web transversely 35 of the warp threads 24 so that these warp threads extend transversely and preferably substantially perpendicularly across the gummed tape strips and thus efficiently increase their transverse strength for the reasons explained. As shown in Fig. 3, an enlarged diagrammatic section taken transversely through such a strip, the warp threads 24 may more nearly retain their shape and the softer filling threads 25 preferably woven under considerably less tension 40 may extend back and forth between the harder warp threads so that these warp threads are in a position to exert more nearly their full strength when a transverse tension 45 is brought to bear on the strip under service conditions. The filling 27 of any suitable material comprising clay, starch or flour as well known in this art, more or less fills the interstices between the threads of the fabric, 50 as is indicated in an exaggerated manner in Fig. 3 so that in this way, if desired, the cloth before gumming may be practically free from pinholes which is advantageous 55 in some classes of work. Fig. 3 diagrammatically indicates the gum coating of any suitable adhesive composition, preferably of somewhat hygroscopic character to facilitate 60 rapid and thorough moistening, which may be applied to one face of the cloth after 65 dyeing or finishing to the extent desired.

If desired, a number of such cloth or other gummed strips may be simultaneously severed from a corresponding series of gummed webs and this series of gummed strips which may have different lengths may be successively moistened and delivered for use as is advantageous for some purposes, such as in carton sealing. For this purpose a series of web rolls 11, 12 and 13 may be mounted so that the webs 1, 2, 3 may be withdrawn 70 therefrom by suitable intermittent feeding devices which may comprise continuously rotating primary supply rolls 4 and suitably connected looper mechanism comprising the looper roll 5 and intermittent feed rolls 6. 75 In this way the webs may be simultaneously fed forward through a space equal to the width of the gummed tape strips desired and then a cutter such as diagrammatically indicated at 7 may act to sever from these webs the series of strips which may be delivered transversely of the webs as by delivery belts 10 diagrammatically shown as arranged on the rolls 8, 9 and delivering the gummed strips, such as 23, between the moistener 14 and presser roll 15 so that they may be properly moistened for use. It is, of course, understood that only a single web roll may be used in such an arrangement as diagrammatically illustrated, and more 90 fully shown and described in my co-pending application, Serial No. 150,667, filed February 24, 1917. The gummed tapes shown and described in this application are not claimed herein, but are claimed in my co-pending application, Serial No. 192,070, filed 95 September 19, 1917.

This invention has been described in connection with a number of illustrative embodiments, forms, arrangements, numbers 105 of parts and elements, materials, constructions and orders of steps and applications or method of use, to the details of which disclosure the invention is not of course to be limited, since what is claimed as new and 110 what is desired to be secured by Letters Patent is set forth in the appended claims.

I claim—

1. The process of making cloth gummed tape strips which comprises weaving a web 115 of fabric having relatively stronger and more numerous warp threads woven at considerably greater tension than the coöperating filling threads so that the warp threads are arranged relatively straighter in the 120 fabric, filling and finishing the fabric to render it substantially impervious and free from pinholes, applying an adhesive gum coating to said fabric and severing relatively narrow gummed tape strips from the 125 end of said web so that the warp threads extend transversely to said strips to increase their transverse strength.

2. The process of making cloth gummed tape strips which comprises weaving a web 13

- of fabric having relatively stronger and more numerous warp threads than the co-operating filling threads, filling and finishing the fabric, applying an adhesive gum coating to said fabric and severing relatively narrow gummed tape strips from the end of said web so that the warp threads extend transversely to said strips to increase their transverse strength.
- 10 3. The process of making cloth gummed tape strips which comprises weaving a web of fabric having relatively stronger warp threads woven at considerably greater tension than the co-operating filling threads so that the warp threads are arranged relatively straighter in the fabric, filling and finishing the fabric, applying an adhesive gum coating to said fabric and severing relatively narrow gummed tape strips from the end of said web so that the warp threads extend substantially perpendicularly to said strips to increase their transverse strength.
4. The process of making cloth gummed tape strips which comprises weaving a web of fabric having warp threads woven at considerably greater tension than the co-operating filling threads so that the warp threads are arranged relatively straighter in the fabric, applying an adhesive gum coating to said fabric and severing relatively narrow gummed tape strips from the end of said web so that the warp threads extend substantially perpendicularly to said strips to increase their transverse strength.
- 25 5. The process of making cloth gummed tape strips which comprises weaving a web of fabric having warp threads relatively stronger and much more numerous than the co-operating filling threads, filling and finishing the fabric, applying an adhesive gum coating to said fabric and severing relatively narrow gummed tape strips from the end of said web so that the warp threads extend transversely and substantially per-
- pendicularly to said strips to increase their transverse strength.
6. The process of making cloth gummed tape strips which comprises weaving a web of fabric having warp threads relatively much more numerous than the co-operating filling threads, applying an adhesive gum coating to said fabric and severing relatively narrow gummed tape strips from the end of said web so that the warp threads extend transversely to said strips to increase their transverse strength.
7. The process of making a number of series of gummed cloth strips the strips having different lengths in each series, which comprises simultaneously and intermittently feeding forward a number of webs of gummed fabric having different widths and severing relatively narrow strips from the ends of said webs and successively delivering said strips transversely of said webs and simultaneously moistening their gummed surfaces.
8. The process of making a number of series of gummed strips the strips having different lengths in each series, which comprises simultaneously feeding forward a number of webs of gummed fabric having different widths and severing relatively narrow strips from the ends of said webs and successively delivering said strips and simultaneously moistening their gummed surfaces.
9. The process of making a number of series of gummed strips the strips having different lengths in each series, which comprises simultaneously feeding forward a number of webs of gummed fabric having different widths and severing relatively narrow strips from the ends of said webs and successively delivering said strips.
